UNITED STATES PATENT OFFICE.

JESSE GRAY ROWE, JR., OF DAVIS, CALIFORNIA.

AUGER AND DRIVER.

1,375,066.

Specification of Letters Patent. Patented Apr. 19, 1921.

Application filed April 27, 1918. Serial No. 231,242.

To all whom it may concern:

Be it known that I, JESSE GRAY ROWE, Jr., a citizen of the United States, residing at Davis, in the county of Yolo and State of California, have invented a new and useful Auger and Driver, of which the following is a specification.

It is the object of this invention to provide a means whereby a hole may be bored in the ground, means being provided whereby a post may be driven into the hole, it being possible to shift the boring means and the driving means horizontally, so that the boring means may first be positioned properly to make the hole, the driving means subsequently being brought into position above the hole, to drive the post.

The invention aims to provide novel means for operating the driving hammer, to provide novel means for rotating the auger or boring element, to provide novel means for feeding the auger downwardly and for raising the auger, and to provide novel means for shifting the hammer and the auger laterally, so that one may occupy the place of the other.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Figure 1 shows in top plan, a machine embodying the present invention;

Fig. 2 is a side elevation of the machine;

Fig. 3 is an end elevation of the machine;

Fig. 4 is a vertical sectional detail, showing a portion of the boring mechanism and cooperating parts, sundry elements appearing in elevation.

The numeral 1 denotes a wheel-mounted vehicle provided adjacent its rear end with a pivot pin 2 on which a frame 3 is mounted to swing horizontally, the frame 3 being upheld by the vehicle 1. The arrows A in Fig. 1 designate the direction in which the frame 3 may be swung horizontally on the

vehicle 1. On the forward end of the vehicle 1 are mounted bearings 4 in which is journaled a vertical shaft 5 adapted to be rotated by a hand wheel 6. A drum 7 is secured to the shaft 5 and is located between the bearings 4. Flexible elements 8 are wound in opposite directions around the drum 7, the flexible elements being carried over idlers 9 on the forward portion of the vehicle 1, the ends of the flexible elements being secured at 10 to the horizontally movable frame 3.

When the shaft 5 is rotated by means of the hand wheel 6, one of the flexible elements 8 is wound upon the drum 7 and the other of the flexible elements is paid off the drum. In this way, a horizontal swinging movement may be imparted to the frame 3, the latter swinging on the pivot pin 2. The object attained by this horizontal swinging of the frame 3 is that first the auger 43, hereinafter described, may be disposed properly to bore a hole in the ground, the hammer 18 (hereinafter described) subsequently being disposed above the hole made by the auger 43, so that the hammer may be used for driving a post or pile into the hole made by the auger.

Upright guides 11 are carried by the forward end of the frame 3, the guides being sustained by rearwardly extended braces 12. The guides 11 are connected at their upper ends by cross bars 14 carrying a bracket 15 on which a sheave 16 is journaled. A flexible element 17 is trained across the sheave, one end of the flexible element being attached to the hammer 18 hereinbefore alluded to, this element being mounted to reciprocate on the guides 11. The rear end of the flexible element 17 is attached to a drum 19 carried by a shaft 20 journaled in bearings 21 mounted on the frame 3. The drum 19 and coacting parts may be of any desired form, the numeral 22 denoting conventionally a brake whereby the rotation of the drum 19 is limited, thereby to hold the hammer 18 against moving downwardly. A gear wheel 23 forms a part of the drum 19 and meshes into a loose pinion 24 on a shaft 25 carried by the bearings 21. A pulley 26 is fixed to the shaft 25. The numeral 28 marks a foot lever constituting a part of a clutch mechanism for coupling the loose pinion 24 to the shaft 25 or to the pulley 26, so that when the pulley 26 is rotated, the pinion 24 and consequently the gear

wheel 23 and the drum 19 will be rotated also. This mechanism may be of any desired form and various mechanisms adapted for the purpose in view are known in the art. The pulley 26 is engaged by a belt 29 trained around a pulley 30 on a shaft 31 constituting a part of an engine 32 mounted on the rear end of the frame 3.

It will be obvious that when the shaft 31 is driven by the engine 32, the pulley 30 will operate the belt 29, the latter driving the pulley 26 and the pulley 26 rotating the pinion 24, the parts 26 and 24 being coupled up releasably by the clutch mechanism of which the foot lever 28 constitutes a part. From the pinion 24 motion is transmitted to the drum 19 by way of the gear wheel 23 and the flexible element 17 may thus be reeled onto the drum 19, elevating the hammer 18. The clutch mechanism of which the foot lever 28 constitutes a part may be manipulated to release the pinion 24 from the shaft 25, the drum 19 being held by the brake 22 until it is desired to drop the hammer 18. Then, by a manipulation of the brake, the drum 19 may be released, and the hammer 18 will ride downwardly on the guides 11 to drive the post or pile.

Standards 33 are erected on the frame 3 to one side of the guides 11 and at the rear thereof, one of the standards being suitably sustained by a brace 34. The standards 33 carry blocks 35; the blocks 35 of the respective standards 33 being connected to angle iron guides 36. The numeral 37 marks an upper cross bar, an intermediate cross bar is shown at 38, and the lower cross bar is shown at 39. The ends of the cross bars 37, 38 and 39 are secured between the angle iron guides 36. The cross bars 37, 38 and 39 carry caps 40 retaining bearings 41, in which an auger shaft 42 is mounted to rotate and to move endwise. Attached to the lower end of the auger shaft 42 is auger 43. The auger shaft 42 is splined as shown at 44 to a pulley 45 supported for rotation in horizontal plane by the lower cross bar 39, the construction being such that when the pulley 45 is rotated, the auger shaft 42 will be rotated also, it being possible for the auger shaft 42 to have a vertical movement in the pulley 45. A belt 46 is trained around the pulley 45 and is engaged around a pulley 47 loose on the engine shaft 31, but adapted to be connected thereto by a clutch 48. When the clutch 48 is thrown in, the pulley 47 will be coupled to the shaft 31. Motion will be transmitted from the pulley 47 by way of the belt 46, through the pulley 45 and thence into auger shaft 42 and the auger 43.

Numerals 49 denotes a cross head in the form of a bar, the ends of which are mounted to slide vertically between the guides 36. The cross head 49 carries a bushing 50 in

which is journaled for rotation, a spool 51 which is flanged to engage the upper and lower edges of the cross head, the spool 51 being keyed as shown at 52 to the auger shaft 42. The auger shaft 42 and the spool 51 rotate with respect to the cross head 49, but when the cross head is raised and lowered, the auger shaft 42 will be raised and lowered also. The means for raising and lowering the auger shaft 42 includes a sprocket chain 53 secured at 54 to the cross head 49, the sprocket chain being trained around a sprocket wheel 55 supported for rotation by the standards 33 and located at the upper ends thereof. The sprocket chain 53 is trained around a sprocket wheel 56 secured to a shaft 57 journaled on the standards 33. A sprocket wheel 59 is loose on the shaft 57, but may be connected thereto by means of a clutch 58. The sprocket wheel 59 is engaged by chain 60 passed around a sprocket wheel 61 secured to the shaft 31 of the engine 32.

The engine shaft 31 drives the sprocket chain 60 by means of the sprocket wheel 61. The sprocket wheel 59 may be coupled to the shaft 57 and be disconnected therefrom by means of the clutch 58. From the shaft 57 motion is transmitted by way of the sprocket wheel 56 and the sprocket chain 53 through a cross head 49, the cross head thus being raised or lowered, by power.

A shaft 62 is supported for rotation on the standards 33 and is adapted to be rotated by a hand wheel 63. A drum 64 is secured to the shaft 62. A flexible element 65 is wound around the drum 64. One end 66 of the flexible element is trained upwardly and then downwardly over an idler 67 carried by the upper cross bar 37 and is attached to the cross head 49. The other end 68 of the flexible element 65 extends upwardly from the drum 64 and is attached to the cross head 49. The shaft 62 may be rotated by means of the hand wheel 63, the end 66 of the flexible element serving to raise the cross head 49 and the auger shaft 42 and the end 68 of the flexible element constituting a means for feeding the cross head and the auger shaft downwardly, the mechanism last above described serving as a means whereby the auger shaft 42 may be raised and lowered manually.

The operation of the device has been dealt with hereinbefore, step by step, in connection with the various component mechanisms, but a résumé will be given at this point.

In order to position the auger 43 properly, the frame 3 may be swung on the pivot pin 2 by means of the hand wheel 6, the shaft 5 and the flexible elements 8. The clutch 28 is manipulated so as to disconnect pinion 24 from pulley 26, thereby preventing the drum 19 from being rotated when

the engine 32 is put into operation. The brake 22 prevents the drum 19 from rotating under the weight of the hammer 18, and the hammer 18 remains elevated as shown in Fig. 3.

The clutch 58 is operated to disconnect the sprocket wheel 56 from the shaft 57. The clutch 48 is operated to connect the pulley 47 to the engine shaft 31. The engine shaft 31 thus is made effective to rotate the auger shaft 42 and the auger 43, through a driving train comprising the pulley 47, the belt 46 and the pulley 45. If it is desired to feed the auger shaft 42 downwardly, by power, then the clutch 58 is thrown into operation, and a positive downward drive is imparted to the auger shaft 42 from the engine shaft 31 by means of the sprocket wheel 61, sprocket chain 60, sprocket wheel 56, and the sprocket chain 53. If the direction along travel of the chain 66 is reversed, the auger shaft 42 and the auger 43 may be elevated. The auger shaft may be raised or lowered by hand, through the instrumentality of the wheel 63, the shaft 62, the drum 64, the flexible element 65.

After a hole has been bored by means of the auger 43, the auger shaft 42 is raised as hereinbefore outlined. The frame 3 may be swung on the pivot pin 2 by means of the hand wheel 6, the shaft 5, and the flexible elements 8, until the hammer 18 is aligned vertically with the hole which has been bored by the auger 43. The clutch 48 is operated to disconnect the pulley 47 from the engine shaft 31, and consequently the auger shaft 42 is not rotated. The clutch 58 is manipulated to disconnect the sprocket wheel 56 from the shaft 57, and no vertical movement is imparted to the auger shaft 42. Through the medium of the clutch operating means 28, controlling the connection between the pinion 24 and the pulley 26, the drum 19 may be operated from the engine 32 to control the reciprocating hammer 18, a driving of a post in the hole bored by the auger 43 thus being brought about.

Having thus described the invention what I claim is:—

1. In a device of the class described, a vehicle; a frame supported on the vehicle;

a rotary boring means journaled on the frame; a post-driving means carried by the frame; an engine on the frame; mechanism 55 for coupling the boring means and the post-driving means to the engine selectively at the will of an operator; and means for pivoting the frame to the vehicle for horizontal swinging movement whereby the boring 60 means and the post-driving means may be brought one at a time into a single vertical plane.

2. In a device of the class described, a vehicle; a frame supported on the vehicle; 65 a boring means; mechanism for mounting the boring means on the frame for rotation and for raising and lowering; a post-driving means carried by the frame; an engine on the frame; mechanism for coupling the 70 boring means and the post-driving means to the engine selectively at the will of an operator; means for raising and lowering the boring means; and means for pivoting the frame to the vehicle for horizontal swinging 75 movement whereby the boring means and the post-driving means may be brought one at a time into a single vertical plane.

3. A device of the class described, constructed as set forth in claim 2, and further 80 characterized by the provision of mechanism for coupling the means for raising and lowering the boring means to the engine, at the will of an operator.

4. In a device of the class described, a 85 vehicle; a frame supported on the vehicle; vertically movable devices for facilitating the setting of a post, carried by the frame; an engine on the frame; mechanism for coupling said devices to the engine selectively to secure vertical movement of said 90 devices; means for rotating one of said devices from the engine; and means for pivoting the frame to the vehicle for horizontal swinging movement, to adjust said devices with respect to the point of application.

In testimony that I claim the foregoing as my own, I have hereto affixed my signature in the presence of two witnesses.

JESSE GRAY ROWE, Jr.
